(57) **CLAIM**

The ornamental design for a display screen with animated graphical user interface, as shown and described.

DESCRIPTION

The file of this patent contains at least one drawing executed in color. Copies of this patent with color drawings will be provided by the U.S. Patent and Trademark Office upon request and payment of the necessary fee.

FIG. 1 is a front view of a first image in a sequence of a display screen with animated graphical user interface showing our new design.

FIG. 2 is a second image thereof.

FIG. 3 is a third image thereof.

FIG. 4 is a fourth image thereof.

FIG. 5 is a fifth image thereof.

FIG. 6 is a sixth image thereof.

FIG. 7 is a seventh image thereof; and,

FIG. 8 is an eighth image thereof.

The broken lines of uneven length show the display screen and form no part of the claimed design.

The appearance of the display screen with animated graphical user interface transitions sequentially between the images shown in FIGS. 1-8. The process or period in which an image transitions to another image forms no part of the claimed design.
